UNITED STATES PATENT OFFICE.

ARNO HOCK, OF KLEIN-ZSCHACHWITZ, NEAR DRESDEN, GERMANY.

FURNACE FOR BOILERS.

1,146,255.

Specification of Letters Patent.

Patented July 13, 1915.

Application filed July 15, 1913. Serial No. 779,190.

To all whom it may concern:

Be it known that I, ARNO HOCK, engineer, citizen of Germany, subject of the King of Saxony and of the Emperor of Germany, residing at Klein-Zschachwitz, near Dresden, in the Kingdom of Saxony and Empire of Germany, have invented new and useful Improvements in Furnaces for Boilers, of which the following is a specification.

10 The present invention relates to an improvement in furnaces for boilers, for instance steam boilers, and in particular such boilers which shall burn for 8-12 hours without any attendance. The object of the 15 present invention is to render the furnace serviceable for the use of various kinds of fuel, and to improve the utilization of these fuels.

A further object of the present invention 20 is to improve the supply of the additional combustion air and to automatically control the entrance of this additional air supply in such a manner, that at the commencement of the working of the respective boiler, a larger 25 quantity of air will enter, and the supply is then gradually reduced until at last the supply of additional air is completely cut off.

The invention is hereinafter described 30 with reference to the accompanying drawing, which shows a preferable constructional form of the subject matter of the present invention in combination with a sectional boiler.

The boiler shown in the drawing consists 35 of several sections *a*, which are connected with each other in a suitable manner, and which form a furnace chamber *b* and horizontally extending flues *c*, *c*¹, *c*², *c*³ for the hot gases. These flues communicate with 40 each other alternately at the front and at the rear side of the boiler, so that the hot gases have to travel along a zig-zag shaped path.

d are the water spaces of the boiler; *e* is 45 the escape flue for the smoke gases; at *f* the hot water or steam leaves the boiler; *g* is a grate formed by a number of bars, which may be of any suitable type, for instance a water-cooled grate; *h* is the ash pit, which 50 is preferably formed by the feet cast to the individual sections.

As usual the air enters through an opening *i* in the ash pit, and rises upward through the grate to the fuel. With ordinary furnaces the air then first passes 55 through the lower layers of fuel, which are

in a hot glow and the hot gases then pass through the upper, not yet glowing layers of fuel. With fuels containing much gases this will have the result that the whole stock 60 of fuel is coked before it is ignited. With some kinds of fuel, such as lignite, this is not advisable, and, on the contrary it will often be preferable, that the air, coming from above, passes down through the not 65 yet glowing layers of fuel to that part of the fuel which is already aglow. After they have then passed through these glowing layers the hot gases mix with the air entering from below, and a very good combustion 70 is obtained. This method of firing is particularly advantageous at the commencement of the working of the boiler, whereas after some time, the air supply from below may gradually be reduced and cease entirely, at the same rate as the fuel is gasified. This object is obtained by means of the furnace inset hereinafter described. In the rear part of the furnace chamber a box-shaped inset *k* is removably fitted. This 75 inset preferably has on its front side an inclined wall *k*¹, with openings *l*. Below the inset is partly closed by a bottom *m*, which rests on the grate, so that air can enter into the inset only through the rear part of the 80 grate *g*¹ which is provided with suitable passages, as indicated by the arrows. The rearmost section of the boiler has two walls *n* and *n*¹, which form a duct *o*. The inset *k* is fitted between the lower ends of the 85 walls *n* and *n*¹ and communicates by means of an opening *p* in its rear wall with the uptake duct *o* formed by said walls. This duct *o* leads above into the first flue *c*. The undermost water filled cross piece of the 90 penultimate boiler section *a* is of such a length that between its rear end and the upper end of the wall *n*, an opening *r* is formed leading from the furnace chamber *b* directly to the first flue *c*. The combustion 95 air, entering the furnace chamber as usual through the grate, can thus pass in the usual manner through the coal heaped on the grate and the hot gases can pass from the fire room *b* through the opening *r* into the first flue *c*. Owing to the arrangement of the inset *k*, however, another portion of the gases may pass from the fire room in the manner of a down draft furnace through the openings *l* into the interior of the inset *k*, and there meet the current of additional air entering through the openings *g*¹. The 100 105 110

hot gases and the fresh air together pass through the opening p and the duct o into the flue e where the gases are ignited. This will result in a complete combustion of the smoke and the utilization of the fuel is considerably improved. A gate r^1 is provided at the upper end of the wall n , which gate may be turned down by means of a handle on the outside, so that it will close the opening r or the duct o , and the hot gases can then pass along only one of the two paths described. For rendering it possible, that the entrance of the additional air through the grate g^1 is gradually shut off in an automatic manner, while the boiler is working, a slanting wall s is provided in the inset, which wall terminates at its lower end above the bottom m , so that a horizontal slot t is formed. Through this slot the additional air must pass. During the working of the boiler ashes will be constantly falling through the openings l onto the slanting wall s and thence down in front of the slot t . Thereby the clear passage of this slot t for the additional air is gradually reduced and after the boiler has been working for some length of time, the entrance of the additional air will be completely cut off, so that the furnace will then work without additional air, as it is desirable according to what has been said hereinbefore. When the boiler is to be heated up afresh the ashes in front of the slot t are removed by means of a scraping iron. Preferably the slanting wall s is made adjustable, as shown in the drawing, by it being hung with a shoulder at its upper end into several hooks s^1 on the rear wall of the inset k , and being held by a support s^2 ; thereby the width of the slot t can be varied, so as to adapt the supply of additional air to the various fuels used. The wall s may, however, also be made integral with the inset k , for instance be cast in piece with the same. The slanting wall may, under circumstances, also be omitted, and then the passages in the grate g^1 will be gradually choked by the ashes falling on them, but the arrangement with the slanting wall s , which forms the horizontal slot, is preferable, as there exists a greater certainty that this slot will be gradually closed during the working of the boiler.

In the duct o preferably a gate, operable from outside is provided, by means of which the draught in this duct can be controlled at will. This gate shall, however, not form any essential part of the present invention.

Various modifications of the arrangement described are further possible, without leaving the principle of the invention.

I claim:

1. In a boiler furnace having a furnace chamber with a grate and an ash pit, the combination of a grate provided with a box-

shaped inset body arranged upon the rear part thereof and having an inclined front wall for supporting a part of the fuel stock, said front wall having openings forming a communication between the furnace chamber and the interior of the inset body, said inset body having also an opening in its bottom wall forming a communication between its interior and the ash pit, an outlet on the upper end of the rear wall, a passage leading from said outlet to the first flue, said passage being tightly closed against the furnace chamber, said first flue having an opening for direct communication with the furnace chamber, and means for reducing the entrance passage of the additional air current from said ash pit to said front wall openings of the inset body.

2. In a boiler furnace having a chamber with a grate, a furnace inset consisting of a removable box-shaped inset-body triangular in cross section arranged upon said grate and having an inclined front wall supporting a part of the fuel stock, said front wall having openings forming a communication between the furnace chamber and the interior of the inset-body, said inset-body having an opening on its lower side adapted to form a communication between its interior and the ash pit and an opening in its rear wall adapted to serve as an outlet for the air and the hot gases; a slanting wall in said inset disposed above the entrance opening from the ash-pit and forming with the bottom of said inset a horizontally extending slot, a passage leading from the opening in the rear of the inset to the first boiler flue and an opening leading from the furnace chamber directly into the first flue.

3. In a boiler furnace having a chamber with a grate, a furnace inset consisting of a removable box-shaped inset-body triangular in cross section arranged upon said grate and having an inclined front wall supporting a part of the fuel stock, said front wall having openings forming a communication between the furnace chamber and the interior of the inset-body, said inset-body having an opening on its lower side adapted to form a communication between its interior and the ash pit and an opening in its rear wall adapted to serve as an outlet for the air and the hot gases; a slanting wall in said inset disposed above the entrance opening from the ash-pit and forming with the bottom of said inset a horizontally extending slot, the said slanting wall being adjustably arranged, a passage leading from the opening in the rear of the inset to the first boiler flue and an opening leading from the furnace chamber directly into the first flue.

4. In a boiler furnace having a chamber with a grate, a furnace inset consisting of a removable box-shaped inset-body arranged upon said grate and having an inclined

front wall supporting a part of the fuel stock, said front wall having openings forming a communication between the furnace chamber and the interior of the inset-body and an entrance for the hot gases, said inset-body being closed below in its front part while at the rear part an opening is provided forming a communication with the ash pit and an entrance for the additional air, the rear wall of said inset-body having an opening adapted to serve as an outlet for the air and the hot gases, an inclined wall in said inset arranged in the rear part of the inset body above the lower opening thereof, and forming a horizontal slot with the bottom of said inset, a passage leading from the said opening in the rear of the inset to the first boiler flue, and an opening forming a communication between the furnace chamber and the first flue.

5. In a boiler furnace having a chamber with a grate, a furnace inset consisting of a box-shaped inset-body arranged upon said grate and having an inclined front wall

supporting a part of the fuel stock, said front wall having openings forming a communication between the furnace chamber and the interior of the inset-body, said inset-body having an opening on its lower side adapted to form a communication between its interior and the ash pit and an opening in its rear wall adapted to serve as an outlet for the air and the hot gases, a passage leading from the said opening in the rear of the inset-body to the first boiler flue and an opening forming a communication between the furnace chamber and the said first flue, a gate operable from outside adapted to close the said passage and the communication between the furnace chamber and the first flue respectively.

In testimony whereof I have hereunto set my hand in presence of two subscribing witnesses.

ARNO HOCK.
